UNITED STATES PATENT OFFICE.

JEROME B. WILSON, OF LANSING, MICHIGAN.

WIRE-MATTRESS STRETCHER.

SPECIFICATION forming part of Letters Patent No. 739,568, dated September 22, 1903.

Application filed October 9, 1902. Serial No. 126,620. (No model.)

To all whom it may concern:

Be it known that I, JEROME B. WILSON, a citizen of the United States, residing at Lansing, in the county of Ingham and State of Michigan, have invented certain new and useful Improvements in Wire-Mattress Stretchers; and I do declare the following to be a full, clear, and exact description of the invention, such as will enable others skilled in the art to which it appertains to make and use the same.

My invention is an improved wire-mattress stretcher especially adapted for use in connection with mattresses which are made of woven-wire fabric for stretching the same; and it consists in the peculiar construction and arrangement of devices hereinafter fully described, and pointed out in the claims.

In the accompanying drawings, Figure 1 is a side elevation of a portion of a wire mattress provided with my improved stretching device. Fig. 2 is a vertical longitudinal sectional view of the same. Fig. 3 is a horizontal sectional view taken on a plane indicated by the line *a a* of Fig. 1.

In the embodiment of my invention here shown the numeral 1 designates a side bar of the mattress, and 2 designates a stretcher-bar, in the present instance the head-bar of the mattress. The said stretcher-bar comprises a pair of sections 3 4, between which one end of the mattress fabric 5 is secured. On the under side of the stretcher-bar is a plate 6. In practice one of these plates is employed at each end of the stretcher-bar. The said plate is preferably made of metal and is provided on its upper side at its ends with upstanding lugs 7 8, which form flanges and coat with the plate to form a seat for the reception of the stretcher-bar. It will be observed by reference to Figs. 1 and 2 of the drawings that the opposing inner sides of these flanged lugs are inclined and converge downwardly, so that the same clamp the sections of the stretcher-bar between them and cause the said sections of the stretcher-bar to bind tightly on the end of the mattress fabric. A screw 9 may be employed also to secure the stretcher-bar on the plate, the said screw passing through the lug - clamp 7, through the section 4 of the stretcher-bar, the mattress fabric, and entering the section 3 of the stretcher-bar. On the under side of

the stretcher-bar plate, at the inner end thereof, are a series of ratchet-teeth 10. A stud 11 depends from the stretcher-bar plate, near the outer end thereof, and is preferably disposed midway between its sides, and at the lower end of the said stud is formed an inwardly-extending arm 12.

In the upper side of the side bar 1, at the end thereof, is recessed a plate 13. The said plate is preferably made of metal and is provided on its upper side at its central portion with a series of ratchet-teeth 14, which engage with the ratchet-teeth of the stretcher-bar plate and coat therewith to secure the stretcher-bar plate, and hence the stretcher-bar, at any desired adjustment, it being understood that the stretcher-bar is movable longitudinally on the said bar, and hence enabling the mattress fabric to be tightened or stretched to the requisite tension. The side bar is provided near its end with a vertical longitudinal slot 15. The plate 13 is provided with a slot 16, which is coincident with the slot 15. A bolt 17 passes through the stretcher-bar, the stretcher-bar plate, operates in the slots of the said bar and its plate, and is provided at its lower end with a nut 18. By this means the stretcher-bar is slidably connected to the side bar. It will be understood that before adjusting the stretcher-bar on the side bar to stretch the mattress fabric the nut on the bolt must be loosened.

In the upper side of the side bar is a longitudinal mortise 19. The side-bar plate 13 is provided on its under side with a corresponding tenon, which is preferably formed integral therewith, and a pin 21 passes through alined transverse openings in the side bar and the said tenon and serves to securely fasten the plate 13 on the side bar.

The lower end of the stud with which the stretcher-bar plate is provided operates in the slot of the side-bar plate. To the said stud is attached the inner end of a link 22, which constitutes a stretcher element and is slotted, as at 23, to enable it to clear the arm of the stud and to form a pivotal connection between the link and the stud, whereby the link may be either extended longitudinally with reference to the side bar or swung laterally out of the way under the stretcher-bar, as will be understood. This link in the form

of my invention here shown is provided with a plurality of openings 24, adapted for the reception of the upper end of a stretcher-lever 25, which may be either of the form here shown or of any other suitable construction. In operation this lever bears against and is fulcrumed on one end of the side bar, as shown in Fig. 1.

It is thought the operation of my invention will be fully understood from the foregoing description, in connection with the drawings.

I do not desire to limit myself to the precise construction and combination of devices hereinbefore shown and described, as it is evident that modifications may be made therein without departing from the spirit of my invention and within the scope of the appended claims.

Having thus fully described my invention, what I claim as new, and desire to secure by Letters Patent, is—

1. In combination with a side bar and an end bar of a wire mattress, said side bar having a vertical, longitudinal slot therein, plates on the opposing sides of said bars and having coacting ratchet-teeth, said side-bar plate having a slot coincident with that of the side bar, and said end-bar plate having a stud on its under side, a link engaged by the stud and thereby pivotally attached to the end-bar plate, and a bolt connecting the side bar and end bar together, operating in the slots of the side bar and its plate, passing through and traveling with the end-bar plate and coacting with the stud to prevent disengagement

of the link from the latter, substantially as described.

2. In a device of the class described, the combination with a side bar and an end bar having mutually-engaging ratchets, a stretcher-link detachably connected to the end bar, and a bolt slidably connecting said bars together, said bolt coacting with the link-attaching means to normally prevent detachment of the stretcher-link, substantially as described.

3. The combination with a mattress side bar, of a stretcher-bar slideable thereon, means to connect them together, and a stretcher element detachably connected thereto and normally locked thereto by the said connecting means, substantially as described.

4. In a device of the class described, the combination of a side-bar plate and a stretcher-bar plate, having mutually-engaging ratchet-teeth, said stretcher-bar plate having a stud to bear and slide on the side-bar plate, a stretcher element engaged by the stud, and means, slidably connecting the said plates together and coacting with the stud to prevent the detachment of the stretcher element, substantially as described.

In testimony whereof I have hereunto set my hand in presence of two subscribing witnesses.

JEROME B. WILSON.
